US00D932216S

(12) **United States Design Patent** (10) **Patent No.:** **US D932,216 S**
(45) **Date of Patent:** **** Oct. 5, 2021**

(54) **TAPERED DRESSER**

(71) Applicant: **Dooli Products, LLC**, New York, NY (US)

(72) Inventors: **David M. Stravitz**, New York, NY (US); **Steven G. Marton**, New York, NY (US)

(73) Assignee: **Dooli Products, LLC**, New York, NY (US)

(**) Term: **15 Years**

(21) Appl. No.: **29/777,971**

(22) Filed: **Apr. 9, 2021**

Related U.S. Application Data

(63) Continuation-in-part of application No. 17/194,401, filed on Mar. 8, 2021, now Pat. No. 11,103,067, which is a continuation-in-part of application No. 17/094,979, filed on Nov. 11, 2020, now Pat. No. 10,939,761, which is a continuation-in-part of application No. 16/992,397, filed on Aug. 13, 2020, now Pat. No. 10,905,241, which is a continuation of application No. 16/986,932, filed on Aug. 6, 2020, now Pat. No. 10,813,456, which is a continuation-in-part of application No. 16/799,909, filed on Feb. 25, 2020, now Pat. No. 10,758,046, and a continuation-in-part of application No. 16/799,941, filed on Feb. 25, 2020, now Pat. No. 10,786,080.

(60) Provisional application No. 62/944,425, filed on Dec. 6, 2019, provisional application No. 62/949,664, filed on Dec. 18, 2019.

(57) CLAIM

The ornamental design for a tapered dresser, as shown and described.

DESCRIPTION

FIG. 1 is a front perspective view of a first embodiment of a tapered dresser showing our new design;
 FIG. 2 is a rear perspective view thereof;
 FIG. 3 is a front elevational view thereof;
 FIG. 4 is a rear elevational view thereof;
 FIG. 5 is a top plan view thereof;
 FIG. 6 is a bottom plan view thereof;
 FIG. 7 is a right elevational view thereof;
 FIG. 8 is a left elevational view thereof;
 FIG. 9 is a front perspective view of a second embodiment of a tapered dresser showing our new design;
 FIG. 10 is a rear perspective view thereof;
 FIG. 11 is a front elevational view thereof;
 FIG. 12 is a rear elevational view thereof;
 FIG. 13 is a top plan view thereof;
 FIG. 14 is a bottom plan view thereof;
 FIG. 15 is a right elevational view thereof;
 FIG. 16 is a left elevational view thereof;
 FIG. 17 is a front perspective view of a third embodiment of a tapered dresser showing our new design;
 FIG. 18 is a rear perspective view thereof;
 FIG. 19 is a front elevational view thereof;
 FIG. 20 is a rear elevational view thereof;
 FIG. 21 is a top plan view thereof;
 FIG. 22 is a bottom plan view thereof;
 FIG. 23 is a right elevational view thereof;
 FIG. 24 is a left elevational view thereof;
 FIG. 25 is a front perspective view of a fourth embodiment of a tapered dresser showing our new design;
 FIG. 26 is a rear perspective view thereof;
 FIG. 27 is a front elevational view thereof;
 FIG. 28 is a rear elevational view thereof;
 FIG. 29 is a top plan view thereof;
 FIG. 30 is a bottom plan view thereof;
 FIG. 31 is a right elevational view thereof;
 FIG. 32 is a left elevational view thereof;
 FIG. 33 is a front perspective view of a fifth embodiment of a tapered dresser showing our new design;
 FIG. 34 is a rear perspective view thereof;
 FIG. 35 is a front elevational view thereof;
 FIG. 36 is a rear elevational view thereof;
 FIG. 37 is a top plan view thereof;
 FIG. 38 is a bottom plan view thereof;
 FIG. 39 is a right elevational view thereof;
 FIG. 40 is a left elevational view thereof;
 FIG. 41 is a front perspective view of a sixth embodiment of a tapered dresser showing our new design;
 FIG. 42 is a rear perspective view thereof;
 FIG. 43 is a front elevational view thereof;
 FIG. 44 is a rear elevational view thereof;
 FIG. 45 is a top plan view thereof;
 FIG. 46 is a bottom plan view thereof;
 FIG. 47 is a right elevational view thereof; and,
 FIG. 48 is a left elevational view thereof.

The broken lines show portions of the tapered dresser, which form no part of the claimed design.
